UNITED STATES PATENT OFFICE.

ADOLPH C. RECKER, OF OAKVILLE, CONNECTICUT, ASSIGNOR TO WATERBURY MFG. CO.,
OF WATERBURY, CONNECTICUT, A CORPORATION.

DESIGN FOR A CARBID-CARRIER.

50,140.

Specification for Design.

Patented Jan. 2, 1917.

Application filed October 26, 1916. Serial No. 127,955. Term of patent 14 years.

To all whom it may concern:

Be it known that I, ADOLPH C. RECKER, a citizen of the United States, residing at Oakville, in the county of Litchfield and State of Connecticut, have invented a new, original, and ornamental Design for a Carbid-Carrier, of which the following is a specification, reference being had to the accompanying drawing, forming part thereof.

Figure 1 is a front view of a carbid car-

rier, showing my new design. Fig. 2 is a side view thereof.

I claim:—

The ornamental design for a carbid carrier, as shown.

ADOLPH C. RECKER.

Witnesses:

J. S. NEAGLE,
FRANK J. KELIHER.
